UNITED STATES PATENT OFFICE.

RUDOLPH A. RIEK, OF RHINELANDER, WISCONSIN.

REFRIGERATOR DOOR.

Application filed March 28, 1927. Serial No. 179,050.

This invention relates to doors for refrigerators and like structures and has reference more especially to means whereby a tight seal can be effected around the door when closed, 5 said door including, as a part of its structure, a means for supporting and backing a sealing gasket extending continuously around the door.

With the foregoing and other objects in view which will appear as the description proceeds, the invention resides in the combination and arrangement of parts and in the details of construction hereinafter described and claimed, it being understood that 15 changes in the precise embodiment of the invention herein disclosed, may be made within the scope of what is claimed, without departing from the spirit of the invention.

In the accompanying drawings the preferred form of the invention has been shown,

In said drawings,

Figure 1 is a front elevation of a door having the present improvements combined therewith.

25 Figure 2 is a view partly in plan and partly in section of a portion of the door, part of the casing being shown in section.

Figure 3 is a perspective view of a portion of the gasket.

30 Referring to the figures by characters of reference 1 designates a pan which can be of porcelained metal, this pan constituting the outer surface of a door 2 of any desired construction. The marginal portion of the pan 35 is formed with a continuously extending flange 3 concavo-convex in cross section and constituting the seat for a continuous packing strip or gasket 4. This gasket can be of any preferred construction. For example it 40 can be made of a rubberized fabric shaped to provide a tubular casing 5 having a compressible filling 6, a flange 7 being extended longitudinally of the casing. The gasket is 45 adapted to rest within the channel provided by flange 3 and the flange 7 of the gasket is

adapted to be attached in any suitable manner to the sides of the door 2 as shown particularly at 8 in Figure 1. Flange 3 is so positioned that when the gasket 4 is seated therein, said gasket will contact with and be 50 partly compressed by the outer surface of the casing C adjacent the door opening O. The hinges H supporting the door can be arranged with their pintles so located as to permit the gasket to swing against and away 55 from the casing C at the hinge side of the door.

Obviously by providing a structure such as described the gasket will be properly backed so as to insure compression at all points when 60 the door is closed. The packing can be renewed readily when worn or otherwise rendered undesirable for further use. The arrangement does not detract from the appearance of the door but, in fact, adds to the appearance 65 thereof by providing a finishing bead extending therearound, this bead being formed of the flange 3. Furthermore the packing is practically concealed and is thus advantageous as compared with other arrangements of gaskets on refrigerators.

What is claimed is:

In a door for refrigerators a porcelained sheet metal pan having an outwardly extended concavo convex flange extending continuously therearound along the free edges thereof, a structure within and projecting from the pan, a gasket extending continuously around the door and seated upon the concave surface of the flange, and an inwardly extending flange on the gasket secured to the projecting portion of the structure in the pan, said flange and its attaching means being concealed between the projecting structure in the pan and the exposed portion 85 of the gasket when the door is closed.

In testimony that I claim the foregoing as my own, I have hereto affixed my signature.

RUDOLPH A. RIEK.
